UNITED STATES PATENT OFFICE

160,229

VENDING MACHINE

Harlan J. Thompson, Los Angeles, Calif., assignor
to General American Transportation Corpora-
tion, Chicago, Ill., a corporation of New York

Application July 27, 1949, Serial No. 4,166

Term of patent 7 years

(Cl. D52—3)

To all whom it may concern:

Be it known that I, Harlan J. Thompson, a citizen of the United States, residing at Los Angeles, in the county of Los Angeles and State of California, have invented a new, original, and ornamental Design for a Vending Machine, of which the following is a specification, reference being had to the accompanying drawing, forming a part thereof.

Fig. 1 is a perspective view of a vending machine showing my new design;

Fig. 2 is a rear elevational view of the machine; and

Fig. 3 is a top plan view of the machine.

I claim:

The ornamental design for a vending machine,
as shown.

HARLAN J. THOMPSON.
